DESIGN FOR A FLAME SHIELD FOR COOK STOVE TOP BURNERS

Claude E. Parker, Chicago, Ill., assignor to Gas
Products Corporation, Chicago, Ill., a corpora-
tion of Illinois

Application August 3, 1940, Serial No. 94,264

Term of patent 7 years

To all whom it may concern:

Be it known that I, Claude E. Parker, a citizen of the United States, residing at Chicago, in the county of Cook and State of Illinois, have invented a new, original, and ornamental Design for a Flame Shield for Cook Stove Top Burners, of which the following is a specification, reference being had to the accompanying drawing, forming part thereof.

Fig. 1 is a plan view of a flame shield for cook

stove top burners, embodying my new design, and showing in dotted outline the remainder of a cover structure for cook stove top burners for illustrative purposes.

Fig. 2 is a perspective view of the flame shield.

I claim:

The ornamental design for a flame shield for cook stove top burners, substantially as shown.

CLAUDE E. PARKER.
